CYLINDER CARRIER OR SIMILAR ARTICLE

Richard M. Peters, Cloquet, and Richard T. Wipson, Duluth, Minn., assignors to Dix, Inc., Cloquet, Minn., a corporation of Minnesota

Filed Dec. 11, 1961, Ser. No. 67,851

Term of patent 14 years

(Cl. D58—26)

FIG. 1

FIG. 2

FIG. 3

FIG. 4

FIG. 5

FIG. 1 is a front elevational view of a cylinder carrier or similar article showing our new design and having foraminous wall structure;

FIG. 2 is a side elevational view as viewed from the left side of FIG. 1;

FIG. 3 is a rear elevational view;

FIG. 4 is a side elevational view of an alternate form of cylinder carrier showing our new design having non-foraminous wall structure; and

FIG. 5 is a top plan view of both forms of our invention illustrated in FIGS. 1-4 inclusive.

The common design presented in the several views includes a base, article receiving wall structure and a vertical supporting member extending upwardly from said base, and an article enclosing collar mounted on

said supporting member and disposed above said wall structure.

The dominant features of our design reside in the portions shown in full lines.

We claim:

The ornamental design for a cylinder carrier or similar article as shown and described.
